ROTARY INTAGLIO PRINTING PRESS

**John B. Paardecamp, Paterson, N. J., assignor, by
mesne assignments, to Interchemical Corpora-
tion, New York, N. Y., a corporation of Ohio**

Application August 3, 1940, Serial No. 350,386

19 Claims. (Cl. 101—157)

This invention relates to rotary intaglio printing presses and aims specifically to provide an improved doctor blade mechanism, ink applicator and substantially completely enclosed fountain housing for a multi-color rotary intaglio printing press having substantially horizontally disposed printing couples.

The usual type of multi-color rotary intaglio printing press includes vertically arranged printing couples in which the impression cylinders are positioned directly above the associated printing cylinders. In order to obtain certain advantages in feeding the web, utilizing waste space beneath the printing couple and increasing the ratio of live web to dead web for more effective drying in shorter space and consequent reduction of problems of register in multi-color printing, it has been suggested that substantially horizontally disposed printing couples be employed. In such printing couples, the impression cylinder is placed at one side of the printing cylinder rather than directly above said printing cylinder as in the usual type of construction, this arrangement providing a printing line at the side rather than the top of the printing cylinder. It has also been suggested that this type of rotary intaglio printing press having horizontally disposed printing couples may be used with the available quick-drying intaglio inks by applying a uniform film of ink to the printing surface substantially immediately beyond the printing line. By so applying the ink the cells of the engraving are protected from evaporation between the printing line and the doctor blade, which, because of the flow of ink removed thereby, is necessarily placed at the side of the printing cylinder opposite the printing line. The conditioned surface of the printing cylinder between the doctor blade and the printing line may then be protected from evaporation of ink by means of a hood or shield conforming to the curvature of the printing cylinder and positioned in close proximity thereto. While this general arrangement of apparatus functions in an entirely satisfactory manner, some difficulties have been encountered which are particularly troublesome when the press is operated at maximum high speed. For example, in order to effect a proper inking of the cylinder, the ink should be supplied at considerable pressure and in large quantities, depending somewhat upon the speed; and for high press speeds splashing of ink creates a noticeable problem. Moreover, due to the placing of the ink applicator immediately beyond the printing line, the applicator is somewhat inaccessible and difficult to ad-

just; and if splashing of ink occurs, there is a tendency to disfigure the freshly printed web.

I have discovered that the above and other difficulties encountered in the construction and operation of multi-color rotary intaglio printing presses having substantially horizontally disposed printing couples may be effectively eliminated, and have provided an improved printing press construction for accomplishing this desirable result.

In accordance with my invention, the ink is applied to the printing surface by means of an improved type of ink applicator which is positioned directly beneath the center of the printing cylinder and said printing cylinder is provided with an enclosure for effectively covering the printing surface from a point substantially immediately beyond the printing line to the doctor blade, so as to eliminate completely any unauthorized passage of ink from the vicinity of the printing cylinder and also, though incidentally, to retard evaporation of ink. My improved substantially completely enclosed fountain housing may comprise a stationary rectangular walled lower portion for the lower half of the printing cylinder and of such size as to accommodate the cylinder of maximum diameter. A vertically movable ink overflow and return pan cooperates with the lower edges of this rectangular walled section and rigidly carries the ink applicator so that mere movement of the return pan into position will result in bringing the applicator into proper relationship with respect to the printing surface after initial adjustments have been made. The entire return pan and applicator are readily removable for cleaning and changing. Cooperating with the stationary lower section of the enclosure, I have provided an upper removable and adjustable housing section which, together with the hood or shield, completes the enclosure for the printing cylinder. This upper section is easily removed for changing printing cylinders and provides suitable supports for the shield, the cylinder end seals and the ends of the usual reciprocating doctor blade. The upper section also includes an adjustable wall portion which is movable to accommodate printing cylinders of different size and the resulting change of position of the doctor blade. My invention also includes a novel mounting for the doctor blade so that it may be moved and maintained in any proper adjusted position regardless of the size of the printing cylinder; and also includes an improved set of operating arms for moving the shield or hood to inoperative position without

causing any interference with the doctor blade or other parts of the printing press.

The above and other features and objects of my invention will become apparent upon consideration of the following detailed description and the accompanying drawings in which:

Fig. 1 is a side elevational view of one unit of a multi-color rotary intaglio printing press in which the essential features of the invention have been included;

Fig. 2 is a transverse vertical sectional view through the printing unit shown in Fig. 1, the view being taken substantially along the line 2-2 of Fig. 4;

Fig. 3 is a fragmentary detail elevational view, 15 partly in section, showing the inoperative position of the movable and adjustable portion of the upper section of the housing;

Fig. 4 is a longitudinal vertical sectional view, taken substantially along the line 4-4 of Fig. 2; 20

Fig. 5 is a fragmentary perspective view showing the mounting and adjusting means for the doctor blade.

I have shown my invention embodied in a 25 printing press having horizontally disposed printing couples and of the type disclosed in Arthur M. Wickwire, Jr., application Serial No. 217,139, filed July 2, 1938, to which reference may be made for a more complete description of the general arrangement of such a press. It is to be understood, however, that the invention is not restricted in its use to a rotary intaglio printing press of the specific character disclosed in said application, but, in its broader aspects, is applicable 35 to rotary intaglio printing presses generally.

Referring now to the drawings, and particularly Figs. 1, 2 and 4, it will be observed that the improved rotary intaglio printing press in which the essential features of my invention have been embodied comprises spaced side frame members F (shown in dot and dash lines) which include substantially horizontally disposed members 18 for supporting a printing cylinder P, vertically disposed members 12 for the mounting of suitable guideways (not shown) for an impression cylinder I, and lower round vertical supporting members 14 for slidably supporting an ink pan carriage C, all as more fully disclosed in said Wickwire application referred to above. It will be noted that the impression cylinder I and the printing cylinder P constitute a substantially horizontally disposed printing couple since said impression cylinder is arranged at the side of the printing cylinder so that a web W may be fed substantially vertically downwardly through said printing couple. Ink is applied to the printing cylinder in the desired quantities, in accordance with my invention, by means of an ink applicator A which is positioned directly beneath the axis of the printing cylinder; and excess ink is removed from the printing surface and said surface conditioned for printing by means of a suitable doctor blade mechanism D. Splashing of ink from the vicinity of the printing cylinder and the ink applicator A is prevented and substantial evaporation of ink solvents is reduced or prevented by means of a suitable enclosure or fountain housing H; and evaporation of ink, or the solvents thereof, from the conditioned portion of the printing surface between the doctor blade D and the printing line is prevented by means of a shield S. My invention consists principally in the novel and improved features of the ink applicator A, the enclosed fountain housing H, the

adjustable doctor blade D and the manner of mounting the shield S, and combinations of these elements with a rotary intaglio printing press of the general character herein disclosed.

I shall first describe the details of construction of the fountain housing H. This will be followed by detailed descriptions of the ink applicator A, the doctor blade D, and the mounting for the shield S.

10 The fountain housing

As shown in Figs. 1, 2 and 4, the fountain housing H comprises a lower stationary, rectangular walled section 16 having a front wall 18, a rear wall 20, and suitable end walls 22, 22 all of which are preferably formed as a single casting of suitable size for the reception of approximately the lower half of the largest size of printing cylinder P. In the drawings, I have shown in dot and dash lines, the position of the largest size of printing cylinder P with reference to the housing H, and in Fig. 2 have also included the position of the smallest size of printing cylinder. Hereinafter when the printing cylinder P is referred to, it is intended to mean the cylinder of largest diameter. The front wall 18 extends from an angular upper edge 24, disposed in the same plane as the upper edge of the horizontal frame member 10 and the center line of the shaft of the printing cylinder, to a lower rounded edge 26 which is positioned a few inches below the bottom of the printing cylinder P, and said wall 18 is provided with a lower finished face 28 and an upper finished face 30. Rear wall 20 extends from a lower rounded edge 32, in the plane of the edge 26, upwardly to an upper flat edge 34 which is positioned about half the distance between the center line of the printing cylinder shaft and the lower edge 32, and has mounted thereon, preferably in fluid-tight relation therewith, a shaft 36 which has connected thereto an arcuate-shaped cover member 38. Shaft 36 for the arcuate cover member 38 is rotatably mounted in the end walls 22 and provided at one end thereof with a knob or handle 40 for turning the cover member 38 to any desired adjusted position, such as indicated in Fig. 2, when the fountain housing is used with printing cylinders of smaller size than the largest diameter printing cylinder P. For accessibility, the shaft 36 may be extended through the horizontal member 10 of the frame F and the handle 40 positioned outside said frame. The cover member 38 may be locked in any desired adjusted position by means of a locking arm 42 provided on the shaft 36 outside the frame member 10 and having an arcuate slot 44 therein through which a locking thumb screw 46 extends and is threaded in the side frames. Each of the end walls 22 has formed integrally therewith a half cylindrical collar portion or member 48 (Fig. 4) through which the shaft of the printing cylinder P is adapted to extend in substantially fluid-tight engagement therewith. Horizontal reinforcing flanges 50 (Fig. 1) are provided at the upper edges of the said half-cylindrical collar member 48 and a vertical supporting or reinforcing rib 52 is provided beneath the central part of said collar 48. A horizontal supporting flange 54 formed at the base of the vertical reinforcing rib 52 provides a support or attaching means for the entire lower stationary portion 16 of the fountain housing H, since said horizontal flange 54 is adapted to rest upon a suitable reinforced bracket 56 secured to the side frames in any suitable manner rigidly to maintain the section 16 of the fountain housing H in the position shown in the drawings. The

end walls 22 are also provided, in the lower portions thereof beneath the supporting flanges 54, with finished faces 58.

All of the finished faces of the lower portions of the walls 18, 20 and 22, 22, cooperate with corresponding finished inside edges 60 provided on an ink return flow and applicator supporting pan 62 which is adapted to close the lower open side of the stationary section 16 of the fountain housing. This pan 62 is provided with rectangular walls corresponding substantially in length with the finished surfaces of the four walls of the section 16 and merging at their lower curved ends in a sloping drain-like bottom 64. The sloping bottom 64 of the ink pan is provided in the lowermost portion with a flanged outlet orifice 66, which is positioned to the left of the center of said pan and may be connected, by a suitable return pipe 68, to an ink reservoir 70. In a position substantially directly beneath the center line of the printing cylinder shaft, the ink pan may be provided with a flanged inlet orifice 72 to which the ink applicator A is attached, as will hereinafter more fully appear, so that ink may be supplied thereto through a supply pipe 74 connected with a pump 76 mounted on or associated with the ink reservoir 70.

Suitable supporting legs 18 are provided on the bottom of the ink pan 62 for supporting said ink pan upon the carriage C for vertical movement up and down beneath the printing cylinder in the manner disclosed in said A. M. Wickwire, Jr., application Serial No. 217,139 referred to above. It will be apparent that the ink pan 62 provides a closure for the bottom of the stationary section 16 of the fountain housing H, which closure has a substantially fluid-tight sealing fit with the finished faces of the rectangular walls of said lower section so that, by movement of the carriage C, said pan may be moved to any desired vertical position for adjustment of the position of the applicator A with respect to the printing cylinder P.

Fountain housing H also includes an upper and removable and adjustable section 80 which cooperates with the upper edges of the lower stationary section 16, the printing cylinder P, the doctor blade D, and the shield S to complete the closure for the major portion of said printing cylinder P. This upper section 80 comprises a pair of end members 82, a forward movable closing or cover member 84 and a pair of end seal supports or supporting segments 86. The end members 82 are of rather unusual shape and each is provided at the lower central portion thereof with a half cylindrical collar member or portion 88, which, together with the collar portion 48 of the lower section 16, complete the enclosure around the shaft of the printing cylinder P. Horizontal supporting flanges 90 are provided on the lower edge of the end members 82 for cooperation with the oppositely disposed flanges 50 of the lower section so that said end members may be removably maintained in proper position by means of screws 92 extending through said flanges.

Each end member 82 extends vertically upward from the horizontal flanges 90 and terminates in an upper curved edge 94 corresponding substantially with, but of slightly larger diameter than, the curvature of printing cylinder P. At the right-hand side thereof, each end member 82 is provided with a cut-out portion 96 which extends inwardly to a point adjacent the collar portion 88 and upwardly substantially two-thirds the height 75

of said end member; and in the upper left-hand corner (Fig. 1) is provided with a cut-out portion 98 which extends inwardly substantially half the distance from a lower left-hand finished edge 100 of said end member 82 to the center line of the printing cylinder and downwardly substantially half the distance from the top edge 94 to the center line of said cylinder or to the flange 90. These two cut-out portions 98 and 96 permit the doctor blade D and the impression cylinder I to be moved to their proper different positions for printing cylinders of smaller diameter, as will hereinafter more fully appear.

It will be noted that the forward finished edge 100 of the end members 82 is aligned with the upper finished face 30 of the forward wall 18 of the lower stationary section 16 of the fountain housing H. Forward movable cover member 84 comprises a front vertically disposed wall 102 which extends across the press slightly beyond the upper end members 82 and is provided with an inside finished face which is adapted to cooperate with the upper finished face 30 of the front wall 18 and the finished edge 100 of each of the end members 82. In normal uppermost position, as illustrated in Figs. 1 and 2, the lower edge of the front wall member 102 is positioned adjacent the angular edge 24 of the front wall 18, and said wall 102 extends upwardly to a curved top sealing blade supporting portion 104. Side walls 106, 106, corresponding in shape to the shape of the cutout portions 98 but of sufficient size to overlap the edges thereof, are provided on or formed integrally with the top portion 104 and are disposed as to fit against and engage with the inside faces of the end members 82. Suitable sealing strips 108, which may consist of one or more thin sheets or strips of flexible sheet metal, rubber, plastic or like material, are secured to the forward edge of the top member 104 and maintained in proper position thereon by means of a clamping rod 110. The sealing strip 108 extends outwardly from the edge of the top member 104 into sealing engagement with the underside of the doctor blade D, and extends longitudinally into frictional engagement with the inner faces of the end members 82 adjacent the left-hand end of the upper edge 94 thereof.

It will be apparent that, since the printing cylinder P ordinarily rotates in a clockwise direction (Fig. 2), the greatest amount of ink thrown from the printing surface will be thrown against the forward wall of the fountain housing which is made up of the walls 18 and 102. To prevent completely the seepage of any ink between the inside finished face of the wall 102 and the cooperating outside finished face 30 of the wall 18, a thin sheet metal double sealing member 112 may be provided. This is removably positioned inside the wall 102 a distance substantially equal to the thickness of the wall 18 and extends through a suitable elongated slot 114 provided in the upper curved top wall or portion 104, a stop member 116 preventing the member 112 from sliding into the housing and maintaining it in proper vertical position.

For accommodating printing cylinders of smaller diameter than printing cylinder P, with a minimum of changeable parts, the upper and forward movable cover member 84 described above is slidable between and on the forward edge 100 of the end members 82 and on the finished face 30, and is also movable to an inoperative position away from the printing cylinder so that access may be gained thereto for cleaning or

changing the printing cylinder or any other desired purpose. To effect these movements of said cover member 84, lugs 118 are formed on said member near the bottom edge of the front wall 102 and pivotally connected by means of links 120 with lever arms 122 mounted on a shaft 124. Shaft 124 is rotatably mounted in a pair of brackets 126 attached to or formed integrally with the stationary lower section 16 of the fountain housing. At one side of the press, said shaft 124 extends through the horizontal member 10 of the side frames F and is provided with an operating crank arm 128 having a handle 130 and an arcuate locking slot 132 which cooperates with a locking screw 134 to maintain the lever arms 128 in any adjusted position. It will be apparent that by moving the crank arms 128 upwardly after loosening the locking screw 134, shaft 124 will be moved in a clockwise direction and, through the crank arms 122, will cause a downward movement of the links 120 and a consequent downward movement of the top and forward movable cover members 84.

Said forward cover members 84 are guided in this downward movement over the finished face 30 by means of guiding screws 136 which pass through elongated vertical guiding slots 138 provided in the forward wall 102 of said members and are threaded into suitable vertically disposed lugs or shoulders 140 provided at the ends of the horizontal flanges 90. By tightening the screws 136 the slidable cover members 84 may be maintained in their proper adjusted positions. In the event that it is desired to gain access to the fountain and the printing cylinder, after moving the doctor blade D and the shield S to their inoperative positions in a manner to be hereinafter described, screws 136 may be removed and the cover member 84 rotated to an inoperative position, such as illustrated in Fig. 3.

As best shown in Figs. 2 and 4, a pair of end seal and shield supports 142 are mounted on the collar portions 88 directly adjacent the inside faces of the end members 82 and held in proper position thereon by means of suitable screws 144. These end seal supports are segmental in shape and extend from a lower edge 144, which is horizontal and may rest upon the right-hand flange 50 of the end walls 22 of the lower stationary section 16, through an arc slightly greater than 90 degrees to a left-hand vertically disposed edge 146, and have an outer curved edge 148 of approximately the same radius, but slightly greater than (Fig. 4), the radius of the printing cylinder P. Sealing members 150 are provided on this curved edge 148 and secured thereto by means of screws 152. These sealing members may be constructed of thin sheet metal, such as brass, steel, copper or the like, and extend inwardly as shown in Fig. 4, over the ends of the printing cylinder P. The distance of the inwardly projecting end of the end seal members 150 from the surface of the printing cylinder varies from approximately $\frac{1}{16}$ of an inch to about $\frac{1}{8}$ of an inch depending upon the particular printing cylinder diameter. Said sealing members 150 extend from the vertical edge 146 around the curved edge 148 to a position as close to the printing line as possible and thereby provide an effective seal for preventing the escape of ink and solvent vapors from the fountain housing H at the ends of the printing cylinder P.

In addition to performing this sealing function, the end seals 150 and the end seal supports 142 also provide a support for the shield S and main-

tain it properly spaced from the surface of the printing cylinder the desired distance. Furthermore, they also act partially to support the doctor blade D for I have provided small supporting blocks 154 on the vertical edges 146 adjacent the top thereof which have their top edges positioned directly in line with the printing surface so as to receive and support the ends of the reciprocating doctor blade D.

The ink applicator

Ink is applied to the printing cylinder P in the desired quantities by means of the ink applicator A. As shown in Figs. 2 and 4, the ink applicator A comprises a substantially triangular or V-shaped casting 160 having an upper substantially horizontally disposed elongated edge 162 of approximately the same length as the printing cylinder P and finished smooth on the inside face thereof. The casting 160 also includes upper vertical side wall portions 164 which extend downwardly a short distance from the upper edge 162 and merge into inwardly sloping side walls 166 which extend downwardly to a flanged base 168 and may be provided, if desired, with suitable reinforcing ribs or flanges 170. The flanged base 168 has a suitable inlet orifice 172 therein and said base is of proper size and shape for attachment to the flanged ink pan orifice 72 by means of suitable screws 174. The casting 160 also includes a back wall 176 which extends downwardly from the upper edge 162 and joins into the side wall portions 164 and 166 and the base 168. As indicated in Fig. 2, said back wall 176 is curved slightly adjacent the base so as to provide with the orifice 172 a suitable ink distributing inlet chamber or portion 178.

Casting 160 also has formed on the inside of the back wall 176 thereof a first and centrally disposed streamlined abutment or baffle 180 and, on either side of the abutment 180, first, second and third similar streamlined abutments or baffles 182, 184 and 186, respectively, these latter baffles being angularly disposed in a somewhat fan-shaped or radial arrangement. Each of the baffles has a lower partially circular curved end and tapers upwardly to a sharp point at the upper end. All of the sharp pointed ends of the baffles are arranged substantially in a straight horizontal line across the entire applicator so as to divide said applicator, or the upper applying edge thereof into eight approximately equal increments of length. The size, shape and arrangement of the baffles is such that, when ink is supplied through the orifice 172 to the initial distribution chamber 178, it will be caused to spread out and be uniformly distributed throughout the entire length of the upper edge 162.

The thickness or depth of each of the baffles corresponds with the height or the width of the sloping side walls 166 of the applicator so that a sheet metal cover member 188, corresponding in shape to the entire triangular shaped applicator, may be secured over the front side of the casting and attached to the side walls 166 and 164 by means of screws 190. As shown in Fig. 2, the cover is flush with the exposed surface of the baffles, so as to divide the applicator into a plurality of chambers. Said cover member 188 is bent inwardly toward the rear wall 176 on a line corresponding to the line formed by the top points of the baffles 180, 182, 184 and 186 so as to form with said rear wall a top triangular shaped chamber 192 having a thin elongated slot or orifice 194 at the top thereof. The slot or

orifice 194 is about $\frac{1}{16}$ of an inch in width and of the same length as the engraved portion of the printing cylinder.

The construction of the applicator A shown in the drawings is designed for a printing cylinder having a printing surface substantially 27 inches in length. With such a length of printing surface, I have found that the seven baffles described, which divide the chamber 192 into the eight uniform increments of length, are sufficient to effect the proper distribution of ink throughout the length of the orifice 194. For such a size of applicator and number of baffles, I have found that a radius of about $\frac{5}{8}$ of an inch for the centrally disposed baffle 180 and of about $\frac{1}{2}$ inch for the other baffles is suitable for the lower circular curved portions thereof. In order to maintain an even distribution of ink throughout the length of the chamber 192 and the orifice 194, the placement of the streamlined abutments or baffles becomes an important factor; and I have found that a uniform distribution of ink throughout the eight increments of length of the applicator can be obtained by placing the baffle 180 above the inlet orifice so that the incoming ink will be divided into two equal parts, one flowing to the right and the other flowing to the left side of the applicator. Then by having the distance between the lower curved part of baffle 182 and wall 166 approximately three times as great as the distance between the lower curved parts of baffles 182 and 180, and the distance between the lower curved part of baffle 184 and wall 166 approximately twice as great as the closest distance between the baffles 184 and 182, and the distance between the lower curved part of baffle 186 and wall 166 substantially equal to the distance between baffles 186 and 184, one quarter of each of the two equal parts of ink divided by the central baffle 180 will be caused to flow to one of the eight equal increments of length of the chamber 192 and orifice 194.

For proper application of ink to the surface of the printing cylinder P, I have found that a maximum space of approximately 0.014 inch between the printing surface and the top edge 162 and orifice 194 of the ink applicator is desirable. A proper setting of the applicator may be obtained by placing a sheet of paper of the desired thickness (approximately 0.014 inch) on top of the applicator before moving the carriage C upwardly on the tubular supports 14 into proper position with the overflow ink pan engaging the lower edges of the stationary rectangular wall section 16. The thickness of the paper then governs the distance between the printing surface and the top of the applicator. Thus, when the applicator is moved into contact with the cylinder having the paper on the top thereof, a suitable stop collar 196 (Fig. 1) provided on the tubular support 14 may be moved into contact with the carriage and there set to determine the proper adjusted position of the applicator. After setting the stop member 196, the carriage C may be lowered and the paper on top of the applicator removed.

Due to the narrowness of the width of the orifice 194, and the volatility of the ink suitable for use in my improved apparatus, it may happen that, during periods of shut-down of the press, the ink will harden and clog the orifice 194. If this occurs, many possible difficulties may ensue when the press is again started and ink is pumped under pressure to the applicator. To prevent this, I have provided an additional elongated ink out-

let or orifice 198 adjacent the orifice 194. This orifice 198 is formed by attaching a suitably shaped narrow plate 200 to the back wall 176 near the top thereof and attaching it thereto by means of screws 202. The shape of the plate 200 is such as to provide a passage 204 beneath the orifice 198 which opens into the chamber 192 of the main portion of the applicator through a plurality of slots or openings 206. This passage 204 and the elongated slot-like orifice 198 may be from $\frac{1}{4}$ to $\frac{3}{8}$ of an inch in width so that there will be no possibility of ink clogging or solidifying therein. Thus, even though the orifice 194 may be clogged, when ink is pumped into the applicator, it will pass through the openings 206 into the passage 204 and to the printing cylinder surface through the orifice 198. Some ink will also pass over to the orifice 194 so that the solvents therein may dissolve any clots or dried particles of ink in said orifice and cause it to open for proper operation.

It will be noted that the upper edge 162 of the main portion of the applicator and the top edge of the plate 200 are curved to conform substantially to the curvature of the printing cylinder. In this way the applicator may be set a uniform distance (approximately 0.014 inch) from the printing surface throughout the width thereof.

The doctor blade mechanism

As best shown in Figs. 1, 2 and 5, the doctor blade mechanism D comprises a suitable thin resilient doctor blade 210 having a reinforcing blade 212 arranged on the top side thereof, both being mounted in a suitable doctor blade holder 214 by means of a clamping plate 216. Doctor blade holder 214 is provided with a suitable groove 218 on the under side of the upper end thereof so that the doctor blade may be removably supported on a rotatable adjusting shaft 220. A shaft 222 suitably supported in the doctor blade holder 214, as by means of clamps 224 (Fig. 1), provides a support for a plurality of curved blade or tension adjusting fingers 226. These fingers are slidably mounted on the shaft 222 and extend forwardly and downwardly from the shaft 222 into contact with the upper reinforcing pressure blade 212. They may be urged into suitable pressure contact therewith by means of pressure adjusting screws 228 which are threaded through extensions 230 provided on said fingers, on the other side of the shaft 222, and adapted to bear against the top side of the doctor blade holder 214. Any desired number of these pressure adjusting fingers may be provided on the shaft 222 and placed at convenient intervals or moved to any desired positions throughout the length thereof for changing or adjusting the pressure of the doctor blade in any portion or portions of its length.

Shaft 220, upon which the doctor blade holder 214 is removably mounted, is rotatably supported in a pair of spaced supporting arms 232 which are rigidly mounted or keyed upon the ends of a primary adjusting shaft 234. Outside the arm 232, on one or both sides of the press, shaft 220 is provided with a rearwardly projecting crank arm 236 and a fork or yoke-shaped adjusting member 238. Arm 236, which is actually rotatably mounted on the shaft 220, has operative connection with said shaft 220 through a pin or lug 240 mounted in said arm and a pair of cooperating adjusting screws 242 mounted in the projecting fingers of the fork or yoke member 238 which is fixed upon the shaft 220. The free end

of crank arm 236 is provided with a locking pin or plunger 244 which is adapted to cooperate with suitable stop or adjustment openings 246 provided in an arcuate-shaped plate attached to or formed integral with the supporting arm 232 between the shafts 220 and 234. It will be apparent that with the mounting construction thus far described for the doctor blade 210, said blade may be given comparatively large angular movements by adjusting the pin 244 to different openings in the member 248, and may then be given any desired finer adjustments by turning the screws 242 so as to move the shaft 220 and the doctor blade relative to the arm 236. In this manner, the angular relation of the doctor blade 210 with reference to the printing surface may be adjusted. Such adjustments of the doctor blade may be called the secondary angular adjustments.

Primary adjusting shaft 234 is rotatably mounted at each end thereof in a suitable hub 250 provided on or formed integral with suitable cross braces 252 for a pair of parallel slide bars 254. As shown in Fig. 1, a gear 256 mounted on the shaft 234 is adapted to mesh with a suitable cooperating helical gear 258 mounted on a stub shaft 260 which is rotatably supported in a suitable bracket 262 secured to one of the cross bars 254. A crank 264 is provided on the outer end of the shaft so that said shaft may be turned to effect a rotative movement of the supporting arms 242 through the gears 258 and 256. Thus, by turning the crank 264 the entire doctor blade mechanism may be moved angularly about the shaft 234. If desired, a suitable locking means 266 may be provided on the shaft 260 between the crank 264 and the bracket 262 for locking the shaft 260 when the proper adjusting movement of the arm 232 has been effected.

The pair of slideable supporting bars 254 are slidably mounted in suitable hubbed openings 268 provided in horizontally disposed arms 270 of a pair of upright supports 272 mounted on the horizontally disposed members 10 of the printing press side frames F. All of the doctor blade mechanism above described, which is supported upon the slideable supporting bars 254, is adapted to be reciprocated in the openings 268 provided in the upright support 272, by connecting one of said bars 254 or cross braces 252 with any conventional type of reciprocating mechanism, such as a suitable cam and lever mechanism associated with the drive of the printing press (not shown).

For moving the entire doctor blade mechanism toward and away from the printing cylinder P along the horizontal members 10 of the printing press frame, the upright supports 272 are provided with grooves 274 in the undersides thereof, which grooves are adapted to engage suitable guide members 276 mounted on the horizontal frame members. The upright supports 272 may be further rigidified and guided in their movement along the guideways 276 by means of suitable guide rods 278 attached to said supports 272 and adapted to slide in openings provided in associated supporting brackets or lugs 280 mounted on the horizontal members 10 of the printing press frame.

To effect the desired movement of the entire doctor blade mechanism along the guideways 276, a screw shaft 282, engaging a suitable threaded opening provided in a lug 284 attached to the upright support 272, is mounted for rotation in a bracket 286 attached to the horizontal press frame member 10 and adapted to be rotated by any suitable gearing 288 connected to a shaft 75

290 which extends across the press and is provided with a suitable crank arm or handle 292 at one end thereof.

With the doctor blade supporting and adjusting mechanism described above, it will be understood that the doctor blade 210 may be moved to substantially any desired angular adjusted position; and also may be moved to the proper angular adjusted position for any desired printing cylinder diameter, such adjusted positions for the actual wiping end of the doctor blade 210 describing a line substantially coincident with the left-hand edge of the endseal support 86.

The shield supporting mechanism

As shown in Figs. 1 and 2 and referred to above, the shield S comprises an arcuate-shaped sheet metal member 296 which conforms substantially to the curvature of the printing cylinder P and is supported at each end upon the endseal supports 86, suitable openings 298 (Fig. 4) being provided for the screws 152 which hold the endseals upon the supports 86. The shield member 296 extends arcuately from the doctor blade 210 substantially to the printing line between the impression and printing cylinders. In order to provide a substantially air-tight shield between the upper end of the shield 296 of the doctor blade a sealing flap 300, of rubber or thin sheet metal, may be provided.

The shield 296 is supported in its operative position on the endseals but may be moved to an upper inoperative position, shown in dot and dash lines in Fig. 1, by means of an upper link 302 pivotally connected to a lug 304 mounted on the top of the shield and a lower supporting link or arm 306 suitably connected to a lug 308 mounted towards the lower end of the shield. Link 306, which, as indicated, is adjustable in length, has a pivotal connection 310 with a lever arm 312 mounted on a shaft 314 journaled in the vertical members 12 of the side frames F. Lever arm 312 is adjustably locked to the shaft 314 by means of an adjustable locking collar 316 and is provided towards its outer end with a flat contacting portion 318. Upon rotation of the shaft 314 in a clockwise direction, the flat contacting portion 318 is adapted to engage a suitable lug 320 provided on a lever arm 322 which is pivotally connected to the link 302 and loosely mounted at its other end on the shaft 314. Shaft 314 is adapted to be rotated by means of a suitable crank arm 324 having a handle 326 at the outer end thereof and a locking plunger 328 centrally disposed thereon for cooperation with suitable openings 330 provided in the vertical frame member 12.

It will be noted that the contacting portion 318 of the lever 312 is normally positioned below the lug 320 so that the lever arm 312 will be rotated a short distance before engagement with lug 320 occurs. Thus, upon moving the crank arm 324 so that the locking plunger 328 engages the right-hand opening 330 in the vertical frame to hold the shield S in the inoperative position indicated in dot and dash lines, lever arm 312 will move upwardly and cause the lower end of the shield 296 to be lifted away from the endseal 150 and the printing cylinder P. The upper end of the shield will remain stationary until the contacting portion 318 engages the lug 320 to cause the lever arm 322 to be moved from that time on simultaneously with the lever arm 312. I have provided this movement for the shield S so that it may be moved to its inoperative posi-

tion without danger of colliding with the doctor blade or any of the other press parts.

From the foregoing description, it will be understood that I have provided an improved fountain housing construction, ink applicator, doctor blade, mechanism and shield removing mechanism for a rotary intaglio printing press of the type including substantially horizontally disposed printing couples. Regardless of the size of the printing cylinder (between certain maximum and minimum limits) said cylinder may be conveniently mounted within a substantially air-tight housing so that all splashing of ink to parts of the press where it is not desired and substantial evaporation of solvents in the ink are eliminated. If a smaller printing cylinder than the printing cylinder P shown in the accompanying drawing is used in the apparatus, the following changes in the parts and the relationship thereof should be made. End seal supporting members 86 and their associated end seals 150 of suitable size for the smaller diameter printing cylinder and a shield S for that smaller size are provided, these being the only actual changes in the parts required to accommodate a smaller diameter printing cylinder. It will be apparent that the cut out portions 96 and the smaller end seal supporting members 86 will allow the impression cylinder to be moved inwardly to have proper contact with the printing cylinder. The adjustable cover 38 will also be moved in a corresponding amount. Overflow ink return pan 62, stop member 196 and the ink applicator A will be readjusted and set to a position above that shown in the drawings 35 for the smaller printing cylinder. Next the upper front cover members 84 are moved downwardly by means of the lever 128 to a position where the sealing member 108 is in close proximity to the surface of the printing cylinder. Then the doctor blade is moved into operative position and the angular relationship thereof with respect to the printing surface adjusted so that the doctor blade 210 will rest on the surface near the end seals 150 and have the 45 ends thereof supported on the blocks 154. Finally, the smaller shield S is moved down into operative position resting on the end seals 150 and having the sealing flap in contact with the top surface of the reinforcing pressure member 212 of the doctor blade.

While I have described a now preferred embodiment of the various features of my invention, it will be readily understood that various changes may be made in the construction shown and described, and certain features may be employed without others, without departing from my invention or sacrificing any of its advantages.

What I claim is:

1. A rotary intaglio printing press, comprising a printing cylinder, an impression cylinder arranged in cooperative relation with said printing cylinder at the side thereof so as to provide a printing line at the side of said printing cylinder, means for applying ink to said printing cylinder, a doctor blade positioned at the side of said printing cylinder opposite the printing line for removing excess ink from said printing cylinder, a fountain housing for enclosing the lower part of the printing cylinder substantially from the printing line to the doctor blade, and means for preventing evaporation of ink solvents from the printing cylinder surface between the doctor blade and the printing line.

2. A rotary intaglio printing press, comprising

5 a substantially horizontally disposed printing couple in which the impression cylinder is arranged at the side of the printing cylinder so as to provide a printing line at the side of said printing cylinder, means for applying ink to said printing cylinder substantially directly below the axis thereof, a doctor blade at the side of said cylinder opposite said printing line, a fountain housing for enclosing said ink applying means and the lower part of said printing cylinder between said printing line and said doctor blade, and means for preventing evaporation from the conditioned surface of said printing cylinder between said doctor blade and said printing line.

10 3. A rotary intaglio printing press, comprising a substantially horizontally disposed printing couple in which the impression cylinder is arranged at the side of the printing cylinder so as to provide a printing line at the side of said printing cylinder, means for applying ink to said printing cylinder substantially directly below the axis thereof, a doctor blade at the side of said cylinder opposite said printing line, 15 a fountain housing for enclosing said ink applying means and the lower part of said printing cylinder between said printing line and said doctor blade, and means for preventing evaporation from the conditioned surface of said printing cylinder between said doctor blade and said printing line, said fountain housing including means for sealing the ends of the printing cylinder substantially between the doctor blade and the printing line.

20 4. A rotary intaglio printing press, comprising a substantially horizontally disposed printing couple in which the impression cylinder is arranged at the side of the printing cylinder so as to provide a printing line at the side of said printing cylinder, means for applying ink to said printing cylinder substantially directly below the axis thereof, a doctor blade at the side of said cylinder opposite said printing line, a fountain housing for enclosing said ink applying means 25 and the lower part of said printing cylinder between said printing line and said doctor blade, and means for preventing evaporation from the conditioned surface of said printing cylinder between said doctor blade and said printing line, said last mentioned means being in sealing engagement with said doctor blade and said doctor blade being in sealing engagement with said fountain housing.

25 5. A rotary intaglio printing press, comprising a substantially horizontally disposed printing couple in which the impression cylinder is arranged at the side of the printing cylinder so as to provide a printing line at the side of said printing cylinder, means for applying ink to said printing cylinder substantially directly below the axis thereof, a doctor blade at the side of said cylinder opposite said printing line, a fountain housing for enclosing said ink applying means 30 and the lower part of said printing cylinder between said printing line and said doctor blade, and means for preventing evaporation from the conditioned surface of said printing cylinder between said doctor blade and said printing line, said fountain housing including an upper movable section which is adjustable to different positions for accommodating printing cylinders of different sizes.

35 6. A rotary intaglio printing press, comprising a substantially horizontally disposed printing couple in which the impression cylinder is ar-

ranged at the side of the printing cylinder so as to provide a printing line at the side of said printing cylinder, means for applying ink to said printing cylinder substantially directly below the axis thereof, a doctor blade at the side of said cylinder opposite said printing line, a fountain housing for enclosing said ink applying means and the lower part of said printing cylinder between said printing line and said doctor blade, and means for preventing evaporation from the conditioned surface of said printing cylinder between said doctor blade and said printing line, said fountain housing including a lower movable section upon which the ink applying means is mounted.

7. In a rotary intaglio printing press having a substantially horizontally disposed printing couple with the printing line at one side of the printing cylinder thereof and a doctor blade at the other side thereof, a fountain housing for enclosing the lower portion of the printing cylinder substantially between said doctor blade and said printing line, comprising a lower stationary rectangular section extending from a horizontal plane passing through the axis of the printing cylinder to a position below the printing cylinder, and an upper movable section adapted to have sealing engagement with said doctor blade and said lower section.

8. In a rotary intaglio printing press having a substantially horizontally disposed printing couple with the printing line at one side of the printing cylinder thereof and a doctor blade at the other side thereof, a fountain housing for enclosing the lower portion of the printing cylinder substantially between said doctor blade and said printing line, comprising a lower stationary rectangular section extending from a horizontal plane passing through the axis of the printing cylinder to a position below the printing cylinder, a movable ink return flow pan in sealing engagement with the lower edges of said stationary rectangular section, and an upper movable section adapted to have sealing engagement with said doctor blade and said lower section.

9. In a rotary intaglio printing press having a substantially horizontally disposed printing couple with the printing line at one side of the printing cylinder thereof and a doctor blade at the other side thereof, a fountain housing for enclosing the lower portion of the printing cylinder substantially between said doctor blade and said printing line, comprising a lower stationary rectangular section extending from a horizontal plane passing through the axis of the printing cylinder to a position below the printing cylinder, a pair of upper stationary end walls mounted on the upper edges of the ends of said stationary rectangular section, and a forward movable cover member in sealing engagement with said end walls, the forward wall of said stationary rectangular section and said doctor blade.

10. In a rotary intaglio printing press having a substantially horizontally disposed printing couple with the printing line at one side of the printing cylinder thereof and a doctor blade at the other side thereof, a fountain housing for enclosing the lower portion of the printing cylinder substantially between said doctor blade and said printing line, comprising a lower stationary rectangular section extending from a horizontal plane passing through the axis of the printing cylinder to a position below the printing cylinder, a pair of upper stationary end walls mounted on

the upper edges of the ends of said stationary rectangular section, means adjacent the inner faces of said end walls for supporting cylinder end seals, and a forward movable cover member 5 in sealing engagement with said end walls, the forward wall of said stationary rectangular section and said doctor blade.

11. In a rotary intaglio printing press having a printing couple and a doctor blade mounted in cooperative engagement with the printing cylinder, an ink fountain housing enclosing the major portion of said printing cylinder below said doctor blade, comprising a stationary rectangular walled section, a movable ink return flow pan in sealing engagement with the lower edges of said stationary section, and means carried by said ink return flow pan for applying ink to said printing cylinder.

12. In a rotary intaglio printing press having a printing couple and a doctor blade mounted in cooperative engagement with the printing cylinder, an ink fountain housing enclosing the major portion of said printing cylinder below said doctor blade, comprising a stationary rectangular walled section, a movable ink return flow pan in sealing engagement with the lower edges of said stationary section, means carried by said ink return flow pan for applying ink to said printing cylinder, and a vertically movable carriage for supporting said ink return flow pan so that said pan and said ink applying means may be moved into and out of operative position.

13. In a rotary intaglio printing press, a printing cylinder, a carriage movable vertically up and down beneath said printing cylinder, an ink return flow pan removably mounted on said carriage, and means mounted on said ink return flow pan for applying ink to said printing cylinder, comprising a substantially triangular shaped member having an elongated orifice in an upper horizontally disposed edge thereof, an ink inlet orifice at the juncture of the other two edges thereof, and means for distributing ink from said inlet substantially uniformly throughout the length of said orifice.

14. In a rotary intaglio printing press, a printing cylinder, a carriage movable vertically up and down beneath said printing cylinder, an ink return flow pan removably mounted on said carriage and having an ink inlet orifice in the bottom thereof positioned substantially vertically beneath the axis of the printing cylinder, and an ink applicator mounted over said orifice and extending upwardly therefrom.

15. In a rotary intaglio printing press, a printing cylinder, a carriage movable vertically up and down beneath said printing cylinder, an ink return flow pan removably mounted on said carriage and having an ink inlet orifice in the bottom thereof positioned substantially vertically beneath the axis of the printing cylinder, an ink applicator mounted over said orifice and extending upwardly therefrom, and a fountain housing positioned around a major portion of said printing cylinder and being in sealing engagement with the upper edges of said ink return flow pan.

16. In a rotary intaglio printing press having a substantially horizontally disposed printing couple with the printing line at one side of the printing cylinder thereof and a doctor blade at the other side thereof, an arcuate shield member positioned over the conditioned portion of the printing surface of said printing cylinder substantially between said doctor blade and said

printing line, and means for moving said shield to an upper inoperative position, comprising a rotatable shaft, a first lever mounted on said shaft for rotation therewith and pivotally connected to said shield at a point adjacent said printing line, and a second lever pivotally connected to said shield at a point adjacent said doctor blade and rotatably mounted on said shaft in a position to be contacted by said first lever and moved thereby so that said shield will first be lifted at the printing line side thereof and will then be lifted at the doctor blade side thereof.

17. In a rotary intaglio printing press, a doctor blade mechanism for removing excess ink from the surface of the printing cylinder, comprising a primary adjusting shaft, a pair of supporting arms mounted on said primary shaft, a secondary adjusting shaft, a doctor blade holder mounted on said secondary shaft for rotation therewith, a resilient doctor blade mounted in said doctor blade holder, means associated with said secondary adjusting shaft and at least one of said supporting arms for rotating said secondary adjusting shaft to different angular positions, and means for rotating said primary adjusting shaft

and the supporting arms carried thereby to different angular positions.

18. An inking apparatus for applying ink to the printing surface of a rotating printing cylinder, comprising a substantially triangular shaped hollow member having an elongated narrow orifice in one edge thereof and an ink inlet orifice at the juncture of the other two edges thereof, and a plurality of streamlined abutments substantially radially arranged within said hollow member for effecting a substantially uniform distribution of ink throughout the length of said elongated orifice.

19. An inking apparatus for applying ink to the printing surface of a rotating printing cylinder, comprising a substantially triangular shaped hollow member having a primary elongated narrow orifice in one edge thereof and an ink inlet orifice at the juncture of the other two edges thereof, baffle means within said hollow member for effecting a substantially uniform distribution of ink throughout the length of said primary orifice, and a secondary orifice wider than said primary orifice and arranged in parallel relation therewith.

JOHN B. PAARDECAMP.
